UNITED STATES PATENT OFFICE

2,555,814

HEAD REST SUPPORT

Newell B. Pulsifer, Livermore Falls, Maine

Application January 16, 1948, Serial No. 2,674

1 Claim. (Cl. 155—173)

1

My invention relates to head rests, and more particularly to head rests which are adapted to be detachably secured to the back of a chair or other seat, and which includes a laterally inwardly-directed portion forwardly of the seat back adapted to receive the head of a person seated in the chair to rest the former.

With the foregoing in view, an object of my invention is to provide an improved head rest.

A further object is to provide an improved head rest which includes bracket means mounting the same on the chair back, universal means mounting the head rest base on said bracket, and a resilient pad detachably secured to said base by a readily detachable sanitary cover.

A further object is to provide a novel and improved base for a head rest which includes a novel head-engaging surface simulating a palm and fingers of the hand.

A further object is to provide a novel base for a head rest which includes the novel hand-simulating surface aforesaid, together with a resilient pad and means for securing said pad on said surface against lateral and endwise displacement.

A further object is to provide a novel bracket for a head rest which includes means for supporting the pad in both an operative and an inoperative position.

Other objects and advantages reside in the particular structure of the invention, combination and arrangement of the several parts thereof, and will be apparent to those skilled in the art upon reference to the attached drawing in connection with the following specification, wherein the invention is shown, described and claimed.

In the drawing:

Figure 1 is a perspective view showing a preferred form of the head rest and mounting means in assembled and operative position relative to a chair;

Figure 2 is an enlarged elevation of the assembled head rest and bracket of Figure 1;

Figure 3 is a top plan view thereof;

Figure 4 is a perspective view of the bracket apart from the rest of the structure;

Figure 5 is a longitudinal vertical section through the head rest and base therefor.

Figure 6 is a plan view of the base plate according to the invention apart from the rest of the structure.

Referring specifically to the drawing, wherein like reference characters have been used throughout the several views to designate like parts, 10 designates generally the seat which in this in-

stance comprises a conventional easy chair. As best seen in Figures 2, 3 and 5, the head rest according to the invention comprises a base 11 having a rear surface 12 and a forward surface 13. 5 The base is also provided with ends 14 and 15.

The base 11 is provided across the front surface between the sides 16 with a relatively shallow transverse recess 17. On either side of the recess 17 the surface 13 slopes outwardly toward the ends 14 and 15 to provide outwardly-sloped surface portions 18 and 19. That outwardly-sloping surface portion 19 which extends toward the end 15 of the base extends further outwardly than does the most forward portion of the outwardly-sloping surface portion 18. Forwardly-directed end flanges 20 and 21 extend from the ends 15 and 14, respectively, of the base, and define the ends and at least adjacent portions of the sides 16. Centrally of the recess 17, the base is formed with 15 a countersunk hole for the reception of a screw or bolt 22 for securing the base to a bracket to be described later.

A pad 23 of any suitable resilient material, such as sponge rubber, is formed to be substantially 25 co-extensive with the forward surface 13 of the base and is seatable thereon between the end flanges 20 and 21. By virtue of the fact that the end flanges encompass at least adjacent portions of the sides 16 of the base, the pad 23 is retained on the forward surface of the base against lateral or endwise displacement by such flanges. A sanitary cover 24 of any suitable washable material and provided with resilient free edges which are inwardly directed encompasses the base and pad to retain the pad thereon against forward displacement relative to the base. Obviously, also, the cover renders the device sanitary and is removable for each separate user if desired.

The screw or bolt 22 aforesaid has a free end 30 extending rearwardly of the base 11, and is detachably secured to one leg of a substantially L-shaped bracket 26. A thumb nut 27, or other readily detachable means, may be utilized to secure the base to the bracket 26. The other leg of the bracket 26 is detachably secured to a laterally-directed end 28 of a bracket arm 29. A suitable bolt 31 and thumb nut 30 may be utilized for this latter connection. It is obvious from the foregoing that the bracket 26, together with the arm 28 of the bracket arm 29 and the bolts 22 and 31, comprise a universal connection between the base 11 and the bracket arm 29. Obviously, other forms of universal connections may be used. The bracket arm 29 includes a

straight rear end portion 30 which is adapted to be readily detachably connected to a plate 31.

The plate 31 comprises a plate portion formed to provide openings 32 therethrough, whereby the same may be readily detachably connected to a side edge of the chair back of the chair 10. A plurality of channel-shaped lugs are formed on the outer surface of the bracket 31 and include a lug 33 which is adjacent the rear edge of the bracket and which is downwardly directed. There is also included an upwardly-directed lug 34 in vertically-staggered relation to the lug 33. The lugs 33 and 34 define a horizontal slideway which is adapted to slidably receive the straight rear end portion 30 of the bracket arm 29 to mount the latter for extensible and retractile movement with respect to the plate 31, which is connected to the side edge of the chair back. In view of the fact that the lug 33 is rearwardly of the lug 34, the weight of the base 11 and forward portion of the bracket arm maintains the bracket arm 29 in a substantially horizontal position in forwardly-located relation to the back rest of the chair. In this position, the forward surface of the base 11 is laterally inwardly-directed relative to the chair in any position permitted by the universal connection of the base with the bracket arm.

The plate 31 is also provided with a laterally inwardly-directed lug 36 and an upwardly-directed lug 35, the latter being located adjacent the bottom edge of the bracket. The lugs 35 and 36 cooperate with the inner side edge of the lug 33 to define a vertically-directed socket which is adapted to receive the end 30 of the bracket arm 29 when it is desired to position the arm and base in an inoperative position. Such position is indicated diagrammatically in broken lines in Figure 2. When it is desired to move the bracket arm 29 from the operative horizontal position to the inoperative vertical position, it is obvious that it is only necessary to pivot the arm upwardly with the lug 33 as a fulcrum and at the same time slide the bracket arm forwardly so that the free rear end thereof will just clear the lower lug 35. To return the bracket arm 29 to the operative position, it is only necessary to rotate the same in a clockwise direction, whereby it will seat itself between the lugs 33 and 34. Thereafter, the user of the device can slide the bracket arm 29 either forwardly or backwardly relative to the chair back to position the base 11 and its pad properly relative to his use.

The plate 31 shown is adapted to be positioned only on the right-hand side edge of the chair back, but it is obvious that by a mere reversal of the lugs thereof, the same can be readily adapted to be positioned on the left-hand side edge of the chair back for users who so prefer that location.

Thus, while I have shown and described what is now thought to be the preferred embodiment of my invention, it is obvious that the same is susceptible of other forms and expressions. Consequently, I do not limit myself to the precise structure shown and described, except as hereinafter claimed.

I claim:

The combination with a chair including a back, of a horizontally disposed support for a head rest positioned along a side edge of said back and mounted on said side edge for extensible and retractile movement, said support comprising a vertically disposed plate positioned along said side edge and detachably secured thereto, opposed guide means carried on the outer surface of said plate, comprising a pair of channel-shaped lugs positioned in opposed relation with respect to each other, one of said lugs being positioned along the upper edge of said plate and adjacent one side of the latter, the other of said lugs being positioned adjacent the other side of said plate in offset relation with respect to said one of such lugs, and a horizontally disposed arm positioned within said guide means and mounted in the latter for extensible and retractile movement with respect to said plate, one end of said arm having means provided thereon for detachably supporting a head rest in parallel spaced relation with respect to the back of said chair.

NEWELL B. PULSIFER.
